[57] CLAIM

The ornamental design for a safety suction fitting for
hydro-therapy spas, as shown and described.

DESCRIPTION

FIG. 1 is a front perspective view of a safety suction
fitting for hydro-therapy spas showing my new design;
FIG. 2 is a rear perspective view thereof; and

FIG. 3 is a cross sectional view taken on line 3—3 of
FIG. 2.

The fragmentary broken line representation of a spa
wall in FIG. 3 is for purposes of illustration only.
